LOW VOLTAGE GENERATOR

Herman G. Fischer, Peter P. Musket, and Donald E. Richardson, Chicago, Ill., assignors to H. G. Fischer & Company, Chicago, Ill., a corporation of Illinois

Application March 23, 1931, Serial No. 524,530

9 Claims. (Cl. 171—97)

This invention relates in general to multi-current generators and while it has more particular reference to multi-current generators for generating electric current of varying wave form for the use in electro-physiotherapy, it will be readily apparent that the invention is capable of employing an apparatus for other and more general use.

A principal object of the present invention is the provision of an apparatus of simple construction and certain operation for producing the various currents desired in electro-physiotherapy, the particular current being provided by the apparatus through simple external controls so constructed and operating that the usual physician can employ the apparatus with certainty and with minimum of directions.

Another important object of the invention is the provision of an apparatus of the character described, the parts of which will be of simple, sturdy construction, and unlikely to require frequent repair, replacement, or internal readjustment in use.

The invention contemplates the provision of a simple low voltage, multi-wave apparatus, for use in electro-physiotherapy, which will produce, at the option of the operator and through the manipulation of simple controls, currents designated as straight galvanic, pulsating galvanic, rapid alternating, galvanic surge, pulsating galvanic surge, rapid alternating surge, slow sinusoidal, pulsating slow sinusoidal, rapid alternating in surges, and various modifications of these current wave forms to provide dwells and periods of rest.

Numerous other objects and advantages of the invention will be apparent as it is better understood from the following description, which, taken in connection with the accompanying drawings, discloses a preferred embodiment thereof.

Referring to the drawings:

Figures 1 to 15 inclusive are diagrammatic views illustrating graphically the wave forms of various current adapted for generation by the apparatus in which the present invention is embodied;

Fig. 16 is a front elevation of an apparatus embodying our present invention, the internal parts being shown in section;

Fig. 17 is an enlarged fragmentary elevation of the commutator and brush mechanism employed in the apparatus;

Fig. 18 is an end view of the brush head and associated parts;

Fig. 19 is a transverse longitudinal section through the collector rings;

Fig. 20 is a section taken substantially on the line 20—20 of Fig. 19;

Fig. 21 is a front elevation of the commutator;

Fig. 22 is a side view thereof; and

Fig. 23 is a wiring diagram of the several circuits of the apparatus.

The apparatus shown on the drawings, and which constitutes the embodiment of the invention at present preferred, comprises generally, an outer housing 31, in which is mounted a motor generator unit 32 having a shaft 33 adapted through suitable friction gearing, generally indicated at 34, to drive a shaft 35 upon which is mounted a set of collector rings 36 and which is provided at its ends with a brush head 37. The brush head 37 carries brushes generally indicated at 38, and which will be presently more fully described. These brushes in their movement engage and move over a commutator 39 to which direct current is supplied by the generator unit 32. The control of the apparatus and the selection of the various wave forms to be produced is accomplished through two switches 41 and 42 which in cooperation with the circuit wiring, illustrated in Fig. 23, determine the current characteristic of the apparatus at each treatment. A main switch 43 is arranged in the circuit as are also volt and ammeters 44 and 45. A rheostat, generally indicated at 46, is provided and controlled by an external knob 47 and a polarity reversing switch 48 is or may be provided if desired.

A motor generator unit, as may be seen from Fig. 23, comprises an electric motor 49, a direct current generator 51, and an alternating current generator or current modulator 52. The motor 49 and the generators 51 and 52 are mounted upon a common shaft 53 which is rotated by the motor. This shaft is provided with a worm 54 which engages a worm gear 55 (Fig. 16) fixed for rotation with the friction disc 34. A friction wheel 56 mounted to slide lengthwise of the shaft 35 may be moved by the hand nut 57 to impart rotation at desired speed to the shaft 35.

Referring more particularly to Figs. 17 to 22, it will be noted that the shaft 35 is provided at its lefthand end with a brush head 58 secured at 59 upon the end of the shaft. This brush head 58 in the instant embodiment of the invention is provided with three sockets, identified by reference characters 61, 62 and 63, in which are mounted three brushes 64, 65 and 66. The shaft 35 is provided with four collector rings, indicated

respectively at 67, 68, 69 and 71. These collector rings are mounted between collars 72 and 73 and are insulated from each other and from the surrounding structure at 74.

5 Wires 75 and 76 lead respectively from brushes 65 and 66 to collector rings 68 and 67. A wire 77 leads from brush 64 to collector ring 69. Viewing Fig. 20, it will be noted that collector ring 71 is divided into segments 78 and 79 insulated from 10 each other at 81. The segment 78 is electrically connected by a wire 82 with the brush 64 so that this brush is electrically connected to both the collector ring 69 and 71. Suitable fixed brushes 83 are provided for continuous engagement with 15 the collector rings as they rotate, and these brushes deliver and receive the current from the stationary portion of the circuit wiring to be presently described.

A commutator or resistance element shown in 20 Figs. 17, 21 and 22, is mounted for engagement by the brushes 64, 65 and 66 as they rotate with the shaft 35. This commutator is built up of a plurality of intermediate parallel bars 84 of relatively narrow sides edges. The bars 84 are insulated from each other at 85. Wider blocks or bars 86 are arranged at the ends or top and bottom of the commutator. The bars 84 and blocks 86 together with the interposed insulation 85 is tightly clamped into a single compact unit by 25 bolts 87, with the presented edges or faces of these parts in a single plane for engagement with the brushes. The blocks 86 and the bars 84 are electrically connected to interposed resistance coils, which will now be described.

30 35 Each bar 84 is extended alternately at its end, as may be seen by comparing Figs. 17 and 21, to provide lugs 88 and 89, and on adjacent bars the position of the lugs is reversed, this arrangement providing room for wires 91 and 92 to be connected to the extended ends or lugs of the bars by 40 soldering or in other suitable manner.

A resistance coil is arranged in the connection between each two successively arranged or adjacent bars 84. These coils, generally indicated 45 at 93, are wound about a carrier 94 arranged back or to the left of the unit formed of the bars 84 and blocks 86. An inlet terminal 95 is connected by a wire 96 with the bottommost bar 84, viewing Fig. 21. This bar is in electrical contact 50 with the bottom block 86. The wiring is such that current passing through the commutator and in at the terminal 95 flows first in and through the bottom bar 84 and block 86, thence serially through the successively arranged bars 84 and 55 the interposed resistance coils 93 to the top bar 84 and top block 86. The last mentioned parts are connected by a wire 97 with a second terminal 98.

60 Wire 101 connects one side of the direct current generator with a wire 102 connected in turn to terminal 95. A wire 103 connects terminal 98 with a wire 104 which in turn is connected to the movable element 105 of the rheostat 46, this rheostat being in turn connected by wire 106 65 with the direct current generator.

The control and selection of the various circuits is accomplished by manipulation of the switches 41 and 42. The switch 41, as indicated in Fig. 23, is a triple switch having three fixed 70 contacts F adapted to be connected by the usual arcuately swinging arm with contacts A, B, C, D and E, a set of which is appropriately arranged for and about each contact F. The switch 42 is likewise a triple switch, having fixed contacts 4 75 adapted for connection with the usual switch

arm with similarly arranged sets of arcuately positioned contacts 1, 2 and 3.

5 After thus describing the major mechanical parts and devices in the apparatus in which the invention is at present embodied, a full understanding of it, it is believed, can be easiest accomplished by a description of the electrical circuits established to produce the current form 10 illustrated in Figs. 1 to 15, and in describing these currents letter and numeral designation is employed in accordance with the switch positions of the switches 41 and 42, the letter designations referring to the contacts A, B, C, D and E of switch 41, and the numeral designations referring to the contacts 1, 2 and 3 of switch 42. It may be mentioned in this connection that like letter and numeral designation of position is indicated upon index plates 107 and 108 arranged upon the front of the casing 31 to guide the physician or other user in the selection of his circuit. It will 20 be understood that the switch 41 is a three arm switch, each arm of which pivots about a terminal F and into contact with the terminals or contacts A, B, C, D and E, the three arms moving together at each switch manipulation. The switch 25 42 similarly is comprised of three arms respectively movable about terminals or contacts 4 and simultaneously into engagement with the three contacts 1, 2 and 3. Each arm in each switch is insulated from other arms and completes its own 30 independent portion of the circuit to be formed.

Circuit A-1, which is the circuit established when contact F is connected with contact A, and contact 4 with the contact 1, provides the straight galvanic current, Fig. 1 of the drawings. 35 The circuit for this current is established as follows: Wire 101 from D. C. generator 51 leads to contact C, which in turn is connected to contact B to contact A. A wire 109 leads from companion contact F to a wave filter 111 (which is or may be provided to reduce or prevent rippling of the various wave forms of the currents provided in the operation of the apparatus). This wave filter is not thought to need particular description since its construction provides no 45 part of the present invention. It may be mentioned, however, that it comprises reactance units 112 and 113 and condensers 114 and 115 suitably wired together. From the wave filter a wire 116 leads to contact points 2 and 1 of the 50 righthand unit of switch 42. From point 1 the circuit continues through contact 4 to wire 117 (in which is or may be arranged the ammeter 45). Wire 117 connects with terminal 118 at the pole changing switch 48 and through the 55 pole changing switch with one or the other of load terminals 119 to which the electrodes delivering the current to the patient is connected. From the pole changing switch the circuit continues through terminal 121 to contact 4 over 60 wire 122. From contact 1 to contact 3 through wire 123 to intermediate terminal F of switch 41 to contact A of this switch and wires 124, 104 to rheostat 46 and thence to wire 106 to generator 51.

A volt-meter 44 may be put across this circuit between contact F of the intermediate unit of switch 41 and contact 1 of righthand unit of switch 42 by wires 125 and 126. A wire 127 leads from contact 1 of lefthand unit of switch 70 42 to wire 128 to the middle of the condensers 114 and 115 on filter 111.

In tracing this circuit, it will be observed that the current passes without alteration through the load terminals 119 and is only affected in its 75

intensity by adjustment of the rheostat 46. The current is a smooth direct or galvanic one without wave or modulation.

The circuit B-1 provides the galvanic surge and its wiring is as follows: wire 101, wire 102 to the commutator and to the point B of left-hand unit of switch 41. One circuit is completed from the commutator by wire 103 through rheostat 46 and wire 106 back to D. C. generator 51. The other circuit continues from B to F, wire 108 to filter, wire 116 to contact 1 of righthand unit of switch 42, contact 4 to wire 117, contact 118, contact 121, wire 122, contacts 4 to 1 of lefthand unit of switch 42, wire 123 to intermediate contact F of switch 41, contact B, wire 129 to collector ring 67 and from this ring to brush 65 in engaging with the commutator. The circuit continues through terminal 98, wire 103, rheostat 46, and wire 106 to D. C. current generator. This circuit includes like connection to wire 123, 127 and wire 128 to intermediate portion of condensers 114 and 115 on the filter 111 and the volt-meter 44 is included in the circuit as earlier described.

Direct current flows through the circuits and the brush 65 in moving over the commutator causes the current to surge from zero to a maximum and back to zero again, as may be observed in Fig. 4.

Current C-1 (Fig. 7) provides a galvanic dwell with the surge and a quarter of the cycle as a rest period for the patient. In this circuit, the current flows from generator 51 as before to the commutator and to contact C of the left-hand unit of switch 41. From this contact to contact F, wire 109 to filter 111, and thence as described in connection with the earlier circuits to wire 116, contacts 2, 1 and 4, wire 117 to terminals 118 and 121 at the pole changing switch. From here the current flows to wire 122, contacts 4, 1 and 3 of lefthand unit of switch 42, and thence by wire 123 to intermediate contact F of switch 41. From here the circuit continues through wire 131 leading from contact C to collector ring 68, and from collector ring 68 to brush 66 and from brush through commutator, wire 103, rheostat 46, and wire 106 to D. C. generator 51.

It will be noted that brush 66 has travelled over the end blocks of the commutator and that when the patient's current reaches a maximum, as occurs when the brush engages the top block (viewing Fig. 23), a dwell is provided which gives the wave form shown in Fig. 7 of the drawings. At the opposite diameter of the movement, the brush 66 is in contact with the bottom block and through the bottom block directly with the wire 103, so that no current flows through the load portion of the circuit or is received by the patient. This gives a rest dwell of zero current. As before, the volt-meter 44 is arranged across the circuit and connection is made with the middle of the filter.

Current D-1 of slow sinusoidal form, as shown in Fig. 10, is produced through the circuit to be now described: wire 101 to wire 102 to terminal 95 of commutator; from commutator the circuit is completed through terminal 98, wire 103, wire 104, rheostat 46, wire 106 to generator. Brush 65 and collector ring 67 are connected by wire 129 to contacts B and D of intermediate switch unit 41. Contact F of this unit is connected by wire 123 to contacts 3 and 1 of lefthand unit of switch 42 and the circuit continues through contact 4, wire 122, terminals 121 and 118, wire 117 to contacts 4, 1 and 2 of righthand switch unit 42, wire 116, filter 111, wire 109 to contact F and D of lefthand unit of switch 41, wire 132 connects this contact D with a collector ring 68 in turn connected with brush 64. It will be noted that the two brushes 64 and 65 travel continuously over the commutator bars 84 and impart modulated current of the true sign form shown in Fig. 10.

Current E-1 (Fig. 10), which is a galvanic surge giving a two-thirds rest period, is provided through wiring as follows: The commutator is supplied with current as described in the immediately preceding circuits and, as before described, is returned to the generator. Brush 65 and collector ring 67 are connected by wire 129, the contacts B, D and E of the intermediate unit of switch 41. Wire 123 connects contact F with contacts 3 and 1 of lefthand unit of switch 42. The circuit continues through wire 122, contacts 121, 118, wire 117 to contact 4 of righthand unit of switch 42; thence by contacts 1 and 2, wire 116, filter 111, wire 109, contact F of lefthand unit of switch 41, and thence by contact E, wire 133 to the active segment of collector ring 71 and to brush 64 at the commutator. By reason of the idle period of the collector ring 71 a two-thirds period of rest is provided in the resulting galvanic circuit.

Current A-2 is the pulsating galvanic current shown in Fig. 2. The circuit comprises wire 101 through contacts C, B and A of lefthand unit of switch 41, wire 108, filter 111, wire 116, contacts 2 and 4 of righthand unit of switch 42, wire 117, terminals 118 and 121, wire 122 to contacts 4 and 2 of lefthand unit of switch 42, wire 134 and wire 135 to A. C. generator 52. The current thence flows by wire 136 to contacts 1 and 3 of lefthand unit of switch 42, wire 123 to contacts F and A of intermediate unit of switch 41, and then back to generator through wire 124, wire 104, movable contact 105, rheostat 46 and wire 106. In the A. C. generator, which is preferably an induction generator, an A. C. current is generated by induction and upon this a D. C. current is superimposed to give the wave form shown in Fig. 2 of the drawings. The field of the A. C. generator is excited by the circuit to be now described: wire 101 to contacts C, B, A, contact F, wire 109 to contacts 4, 2, 3 of intermediate unit of switch 42, wire 137 to generator 52, wire 136 to contacts 1 and 3 of lefthand unit of switch 42, wire 123 to contact F of intermediate unit of switch 41, contact A of this unit, wire 124, wire 104, rheostat 46, and wire 106 to D. C. generator. At the A. C. generator, wire 136 is provided to connect both to the field and to the armature, as may be seen in Fig. 23.

Current B-2 of Fig. 5 is like B-1 of Fig. 4, except that here also the current is converted from galvanic to pulsating galvanic. The circuit comprises wire 101 to contacts C and B of lefthand unit of switch 41, wire 109 of contact F to filter 111, wire 116 to contacts 2 and 4 of righthand unit of switch 42, wire 117 to terminals 118 and 121, wire 122 to contacts 4 and 2 of lefthand unit of switch 42. The circuit then continues through wires 134 and 135 to A. C. generator, from the A. C. generator wires 136 and 127 connect contacts 1 and 3 of lefthand unit of switch 42. Wire 123 leads from contact 3 to contact F of intermediate unit of switch 41 which is connected to contact B in turn connected by wire 129 to collector ring 67 of brush 65 in engagement with the commutator. The circuit is completed through terminal 98, wire 103, wire 104, rheostat 46 and wire 106.

106 to D. C. generator 51. The field of the A. C. generator is excited as just above described in connection with current A-2.

Current C-2 is the pulsating galvanic dwell surge with the one-quarter rest period shown in Fig. 8. This circuit comprises wire 101 to the point C of the lefthand unit of switch 41, wire 109 to filter 111, wire 116 to contacts 2 and 4 of the righthand unit of switch 42, wire 117, terminals 118, 121, wire 122 to contacts 4 and 2 of the lefthand unit of switch 42, wire 134, wire 135 to A. C. generator 52, wire 136 to contact points 1 and 3 of the lefthand unit of switch 42, wire 123 to contacts F and C of the intermediate unit of switch 41, wire 131 to collector ring 68 and brush 66 in engagement with the commutator. From the commutator, the circuit is completed through terminal 98, wire 103, movable contact 105, rheostat 46 and wire 106 to D. C. generator 51. Comparison is suggested between this current and its circuit and the current and circuit of the galvanic dwell surge of Fig. 7. The field of the A. C. generator is excited as just above described in connection with current A-2.

Current D-2, which is the pulsating slow sinusoidal current of Fig. 11 is produced as follows: wire 101 leads to wire 102 and the terminal 95 of the commutator and an energizing circuit is completed from terminal 98, wire 103, wire 104, rheostat 46 and wire 106 back to D. C. generator 51. Brush 65 in contact with this generator and its collector ring 67 are connected by wire 129 to contacts B, D of intermediate unit of switch 41. Wire 123 connects contact F of this unit with contacts 3 and 1 of lefthand unit of switch 42 and wires 127 and 136 connect to A. C. generator 52. From the A. C. generator wire 135 and wire 134 lead to contacts 2 and 4 of lefthand unit of switch 42 and the circuit continues to terminals 121 and 118, wire 117, contacts 4 and 2 of righthand unit of switch 42, and wire 116 to filter 111. From the filter 111, wire 109 leads to contacts F and D of lefthand unit of switch 41 and from contact D wire 132 leads to collector ring 69 of brush 64. The field of the A. C. generator is excited as just above described in connection with current A-2.

Current E-2, which is the pulsating galvanic surge with the two-thirds rest period, and which is illustrated in Fig. 14, is produced as follows: The current, as earlier described, is caused to flow from the D. C. generator through the commutator and back to the generator. The circuit for supplying this current to the terminals 118 and 121 is as follows: brush 65 and collector ring 67 are connected by wire 129 to contacts B, D and E of intermediate unit of switch 41. Contact F of this unit is connected by wire 123 to contacts 3 and 1 of lefthand unit of switch 42. From the contact 1 of this switch wires 127 and 136 lead to A. C. generator 52. From this generator, wire 135 and wire 134 lead to contacts 2 and 4 of lefthand unit of switch 42. The circuit continues in sequence as follows: wire 122, terminals 121 and 118, wire 117, contacts 4 and 2 of righthand unit of switch 42, wire 116, filter 111, wire 109, contacts F and E of lefthand unit of switch 41, wire 133, active segment of collector ring 71 and brush 64. The field of the A. C. generator is excited as just above described in connection with current A-2.

Current A-3 is the rapid alternating current illustrated in Fig. 3 of the drawings. The circuit for it in sequence is as follows: Wire 101, contacts C, B and A of lefthand unit of switch 41,

contact F, wire 109 to contacts 4 and 3 of intermediate unit of switch 42, wire 137 to A. C. generator 52, wire 136, contacts 1 and 3 of lefthand unit of switch 42, wire 123 to contacts F and A of intermediate unit of switch 41, wire 124, wire 104, rheostat 46 and wire 106 to D. C. generator 51. The circuit thus completed is a generating or field circuit for the A. C. generator. From the A. C. generator a delivery circuit is formed as follows: wire 135, wire 138, contacts 10 3 and 4 of righthand unit of switch 42, wire 117, terminals 118 and 121, wire 122, terminals 4, 3 and 1 of lefthand switch unit of switch 42, wire 127 and wire 136 back to A. C. generator.

Current B-3, which is the rapid alternating 15 current in surges, is illustrated in Fig. 6, and is produced by creating a field or delivery circuit in the A. C. generator. Wire 101 leads to contacts C and B of lefthand unit of switch 41, wire 109 leads to contact 4 of the intermediate unit 20 of switch 42, and wire 137 connects contact 3 of this unit to the field of the A. C. generator 52. From this field, wires 136 and 127 lead to contacts 1 and 3 of lefthand switch unit of switch 42, and wire 123 leads to contact F of the intermediate unit 25 of switch 41. The circuit continues: Contact B, wire 129, collector ring 67, brush 65 to the commutator and from the commutator by wires 103, 104 to rheostat 46 and wire 106 to the D. C. generator. The delivery circuit is 30 the same as that already described for circuit A-3.

Current C-3 is the rapid alternation in dwell surges with the quarter rest period as shown in Fig. 9. A field circuit for the A. C. generator 35 is provided as follows: Wire 101 to contacts C and F of lefthand unit of switch 41, wire 109 to contacts 3 and 4 of intermediate unit of switch 42, wire 137 to A. C. generator, wire 136 and wire 127, contacts 1 and 3 of lefthand unit 40 of switch 42, wire 123 to contacts F and C of intermediate unit of switch 41, wire 131 to collector ring 68 and brush 66, to terminal 98, wire 103, wire 104, rheostat 46 and wire 106 to D. C. generator. The delivery circuit is the same as 45 that already described in connection with the immediately preceding circuit, series 3.

Current D-3 is the current of Fig. 12 producing 50 rapid alternations in surges (see Fig. 6). Here the field circuit is energized as follows: Wire 101 from the A. C. generator 51 connects by wire 102 with terminal 95 of the commutator. The current flows through the resistances of the commutator to terminal 98 and back through wire 103, wire 104, rheostat 46 to the D. C. generator 51. Brush 65 55 and collector ring 67 are connected by wire 129 to contacts B, D, and F. The circuit continues in sequence as follows: wire 123, contacts 3 and 1 of lefthand unit of switch 42, wire 127, wire 136, the field of A. C. generator 52, wire 137, contacts 3 60 and 4 of intermediate unit of switch 42, wire 109 to contacts F and D of lefthand unit of switch 41, wire 132 to collector ring 69 and brush 64. The delivery circuit is that already described in connection with the circuit of the 3 series now being 65 described.

Circuit E-3, which is the rapid alternating circuit with the two-thirds rest period, shown in Fig. 15, is produced as follows: The current is caused to flow through the commutator as earlier described. The brush 65 and collector ring 67 are connected by wire 129 to the contacts B, D, E and F of intermediate switch unit of switch 41. Wire 123 leads to contacts 3 and 1 of lefthand unit of switch 42, and wire 127 and 136 to one side of the 70 75

- field of A. C. generator 52. Wire 137 leads to contacts 3, 4 of intermediate unit of switch 42, and wire 109 connects these contacts with contacts F and E of the lefthand unit of the switch 41. The 5 contact E is connected by wire 133 with segmental collector ring 11 and brush 54. The delivery circuit is the same as series 3.
- In connection with the circuits of the E series, the rest period may be increased or diminished by 10 a circuit short-circuiting a portion of the commutator. This circuit comprises wires 141 and 142 leading respectively from taps 143 and 144 at the commutator and connecting to terminals F and E of the righthand unit of switch 41.
- 15 In all of the foregoing circuits, the volt meter 44 is connected as described in explanation of circuits A-1 and B-1 and similar wiring is provided to tap into the center of the filter, as earlier described.
- 20 It is thought that this invention and many of its attendant advantages will be understood from the foregoing description, and it is apparent that various changes may be made in the form, construction and arrangement of the parts without departing from the spirit and scope of the invention or sacrificing all of its material advantages, the form hereinbefore described being merely a preferred embodiment thereof.
- We claim:—
- 30 1. An apparatus for generating currents of wave form for use in electro-physiotherapy and for other uses, comprising in combination, a series of contact bars arranged with their edges in a single plane, resistances interposed between 35 and connected to said contact bars in electrical series, terminals at the ends of the series of bars, a direct current generator connected with said terminals, a brush having relative movement over said contact bars for variously receiving current 40 therefrom, a source of alternating current, a pair of load terminals and selectively operable means for making, varying and breaking connections between said load terminals and said brush, and also between said load terminals and said source 45 of alternating current to superimpose an alternating current upon the direct current passing between said load terminals.
2. An apparatus for generating current of wave form for use in electro-physiotherapy and for 50 other uses, comprising in combination a direct current generator, an alternating current generator, a rotary commutator consisting of a plurality of axially aligned rings, a plurality of brushes severally connected with said rings, said 55 brushes being movable jointly with said rings, resistance elements over which said brushes are maintained in sliding engagement, said resistance elements being connected with the direct current generator, selectively operable means for 60 altering the connection between said resistance elements and said generator, and selectively operable means for establishing connection between said alternating current generator and said brushes to superimpose the alternating current of said alternating current generator upon the direct current, the selectively operable means interposed between the alternating current generator and the brushes being connected with load 65 terminals for leading off the modified current.
3. An apparatus for generating current of wave form for use in electro-physiotherapy and for other uses, comprising in combination, a series of contact bars arranged with their edges 70 in a single plane, resistances interposed between and connected to said contact bars in electrical series, terminals at the two ends of the series of bars, a direct current generator connected with said terminals, a brush mechanism having relative movement on said contact bars for receiving current therefrom, said brush mechanism including a plurality of brushes, a pair of load terminals, a source of alternating current, and means for variously connecting said brushes and said alternating current with said load terminals to superimpose an alternating current upon the direct current passing between said load terminals.
4. An apparatus for generating current of wave form for use in electro-physiotherapy and for other uses, comprising in combination, a series of contact bars arranged with their edges in a single plane, resistances interposed between and connected to said contact bars in electrical series, terminals at the two ends of the series of bars, a direct current generator connected with said terminals, a brush mechanism having relative movement on said contact bars for receiving current therefrom, said brush mechanism comprising three brushes, load terminals, a source of alternating current, and means for selectively connecting said brushes in pairs and said source of alternating current to said load terminals to superimpose an alternating current upon the direct current passing between said load terminals.
5. An apparatus for generating current of wave form for use in electro-physiotherapy and for other uses, comprising in combination, a series of contact bars arranged with their edges in a single plane, resistances interposed between and connected to said contact bars in electrical series, terminals at the two ends of the series of bars, a direct current generator connected with said terminals, a brush mechanism having relative movement on said contact bars for receiving current therefrom, said brush mechanism comprising three brushes, a source of alternating current, load terminals, and means for selectively connecting said brushes singly and in pairs to said load terminals and also for selectively connecting said source of alternating current to said load terminals to superimpose an alternating current upon the direct current passing between said load terminals.
6. An apparatus for generating current of wave form for use in electro-physiotherapy and for other uses, including an aggregate consisting of an aligned motor, direct current generator and alternating current generator, a commutator having a plurality of axially aligned electrically insulated rings, said commutator being rotated by said motor, a plurality of brushes severally conductively connected with said rings and also rotated by said motor, a plurality of aligned resistance bars over which said brushes travel while successively engaging different bars, the resistance elements being connected with said direct current generator, a plurality of switches interposed between said direct current generator, and some of said brushes, and adapted to vary the electric connection between said commutator rings and said generator, and another plurality of switches interposed between said alternating current generator and said first named switches additionally to vary the relation of said brushes to said resistances and to superimpose an alternating current of selectively variable form upon the direct current of selectively variable form.
